UNITED STATES PATENT OFFICE

2,477,215

PAGE LIFTER

Herman Stöttum, Oslo, Norway

Application November 24, 1945, Serial No. 630,671
In Norway November 2, 1943

2 Claims. (Cl. 281—15)

1

This invention relates to musical note-books or the like and the object of the invention is to provide means, which will facilitate the turning of the pages when the musical note-book is in use. The means according to this invention can of course also be used in connection with other books or pamphlets, when it is desirable to provide for easy turn over of the pages.

For this object the invention principally consists in that to the right hand page of the book, preferably very close to the edge of same, there is attached a ribbon or the like, the other end of which is attached to the left hand page of the book adjacent the right hand side of this page, the said ribbon being given such a length, that the right hand edge of the right page will be tightened and lifted up from the page beneath it when the book is opened.

The structure according to this invention is very simple and will have very little effect on the appearance of the book when it is closed, and its function takes place automatically when the book is opened.

In order that this invention shall be easily understood, it will be described hereinafter with reference to the drawing, showing a preferred embodiment.

In the drawing Fig. 1 is a fragmentary plan view of a musical note-book in open position.

Fig. 2 is a side view of the book, seen from the lower edge thereof.

Fig. 3 is a view similar to Fig. 2 but as shown just at a time when one page is turned over.

In the drawing 1 denotes the left hand page of the musical note-book, 2 the right hand page. To the right hand page close to its edge there is attached one end of a ribbon 3, the other end of which is attached to the left hand page 4. The attachment of the ribbon to the right hand page may be very close to the edge of the page or, if desired, in the neighborhood of the middle part of the same. The attachment of the ribbon to the left hand page is adjacent to the right hand edge of the same, the length of the ribbon 3 is so chosen, that it is shorter than the distance

2

between the two points of attachment when the book with its pages in open position is placed on a flat table, whereby the ribbon 3 will perform a lifting of the lower right corner of the right hand page when the book is opened, as can be seen in the drawing.

When the page 2 is turned over from the right hand side to the left side, as shown in Fig. 3, the ribbon 3 will bend itself about its attachment place 4, and will not prevent the complete turnover of the page 2 on the left hand.

I claim:

1. A device to facilitate the turning over of the pages in books attached together along one side forming the back of the book, said device consisting in a ribbon of flexible material attached at one end to one of two adjacent pages, and at the other end to the other of said two pages, the straight line distance between the two points of attachment with the pages opened up in the same plane being shorter than the length of the ribbon, and the point of attachment to the left hand page being close to the meeting line between the pages, while the point of attachment to the right hand page is in the neighborhood of the outer edge of the same.

2. A book comprising a plurality of pages, and a ribbon connected to at one end to the upper surface of the left of a pair of open pages adjacent the right edge thereof, and at the other end to the upper surface of the right page adjacent the right edge thereof, said ribbon being of a length less than the distance between the points of attachment to the page when said pages are open, but greater than the distance between the points of attachment when the pages are closed.

HERMAN STÖTTUM.
